DESIGN FOR A COMBINED CIGARETTE PACKAGE RECEPTACLE AND MATCH PACKAGE HOLDER

Frank L. Grant, Euclid, Ohio

Application September 19, 1938, Serial No. 79,981

Term of patent 3½ years

To all whom it may concern:

Be it known that I, Frank L. Grant, a citizen of the United States, residing at Euclid, in the county of Cuyahoga and State of Ohio, have invented a new, original, and ornamental Design for a Combined Cigarette Package Receptacle and Match Package Holder, of which the following is a specification, reference being had to the accompanying drawing, forming part thereof.

Fig. 1 is a perspective view of a combined cigarette package receptacle and match package holder showing my new design, and

Fig. 2 is a similar view showing the opposite side thereof.

I claim:

The ornamental design for a combined cigarette package receptacle and match package holder, substantially as shown.

FRANK L. GRANT.
